United States Patent Office.

JAMES T. GILMORE, OF PAINESVILLE, OHIO.

Letters Patent No. 85,737, dated January 12, 1869.

IMPROVED MACHINE FOR TRAMMING AND DRESSING MILLSTONES.

The Schedule referred to in these Letters Patent and making part of the same.

To all whom it may concern:

Be it known that I, JAMES T. GILMORE, of Painesville, in the county of Lake, and State of Ohio, have invented a new and useful Improvement in Machines for Tramming, Staffing, and Dressing Millstones; and I do hereby declare that the following is a full, clear, and exact description thereof, which will enable those skilled in the art to make and use the same, reference being had to the accompanying drawings, forming part of this specification.

This invention relates to a new and useful improvement on a machine for tramming, staffing, and dressing millstones, for which Letters Patent were granted to me, bearing date October 28, 1862.

The present invention consists in a modification of the construction of the machine as originally patented, whereby the guide on which the cutter-stock works is rendered adjustable in a vertical plane, so that the cutter may be moved, or made to work, in a line slightly inclined from a horizontal plane, and the face of the stone dressed in disk-form, or slightly concave from its "skirt" or periphery towards its centre, and a proper "bosom" given the stone, as hereinafter fully shown and described.

In the accompanying sheet of drawings—

Figure 1 is a plan or top view of my invention.

Figure 2, a side view of the same.

Figure 3, a section of the same, taken in the line z z , fig. 1.

Similar letters of reference indicate corresponding parts.

A represents an upright hollow journal, provided with a flange, B, at its base, having three lugs or ears, at equal distances apart, through which set-screws a pass, to admit of the adjustment of the journal at right angles with the base of the stone, the journal being secured to the spindle of the stone when the bed-stone is being operated upon, and secured or clamped to the bail when the upper stone or runner is being operated upon.

These parts are or may be substantially the same as shown in the originally-patented machine.

C is an arm, having a sleeve, D, at its inner end, which sleeve is fitted on the journal A, and secured thereto by screws b .

This sleeve is allowed to turn freely on the journal A, and the arm has a tangential position with the journal, as shown clearly in fig. 1.

This arm and the sleeve are substantially the same as shown in the original patent, and therefore do not require a minute description.

E is a guide, which extends the whole length of the arm C, and is pivoted to it, as shown at c in fig. 2, the pivot c passing through the inner ends of the guide and arm.

The guide is secured to the arm by set-screws d , which pass through oblong slots, e , in the arm, and into the rear side of the guide. (See fig. 3.)

By slightly unscrewing the screws d , the guide, it will be seen, may be raised or lowered from the pivot c as a centre, and secured at a slight angle from a horizontal plane.

F is the cutter-stock, which is fitted on the guide E, and allowed to slide freely thereon.

The guide may be of dovetail-form, as originally made, and shown in the accompanying drawings, or it may be constructed in other ways.

From the above description, it will be seen that the cutter in stock F is moved in a right line, and, by adjusting the outer part of the guide E in a slightly-elevated position, the face of the stone will be cut slightly concave from its skirt or periphery to its eye.

This will be fully understood by referring to fig. 2, in which the dotted line e' represents the upper surface of the stone previous to being dressed, and the line f the upper surface of the stone after being dressed.

The line f , it will be seen, gradually inclines downward from the skirt or periphery of the stone to the eye g , so as to form what is technically termed the bosom, said inclination being due to the elevation of the outer part of the guide E.

Thus it will be seen that, by a very simple modification of the original machine, I may give a millstone the requisite "bosom" by a trifling adjustment of the guide E.

I claim as new, and desire to secure by Letters Patent—

Pivoting the guide E to the arm C; and making said guide adjustable on the arm, for the purpose of giving the necessary dish or "bosom" to the millstone, in the manner substantially as herein set forth and shown.

JAMES T. GILMORE.
